UNITED STATES PATENT OFFICE.

FRITZ ANDORFF, OF VIERNHEIM, GERMANY, ASSIGNOR TO AKTIENGESELLSCHAFT BROWN, BOVERI & CIE., OF BADEN, SWITZERLAND, A JOINT-STOCK COMPANY.

HIGH-TENSION BUSHING TRANSFORMER.

Application filed December 13, 1926, Serial No. 154,445, and in Germany December 24, 1925.

This invention relates to lead bushings for high voltage apparatus, such as circuit breakers, or transformers, and it has particular relation to instrument transformers, or similar devices associated with such bushings.

Difficulties are very often experienced in the construction of instrument transformers for high voltage apparatus, inasmuch as the low voltage windings must be maintained at a relatively low potential so as to eliminate any danger to the metering and switching equipment and personnel which comes in contact therewith, and it has, on the other hand, to be closely interlinked with the high voltage parts of the circuit with which it is to co-operate in transformer relationship.

The difficulties are less pronounced in cases where single-turn current transformers may be provided inasmuch as the straight-through conductors passing through the walls of the high voltage apparatus in the center of the lead bushings may be utilized as the primary winding, and the secondary winding may be arranged on an iron core disposed concentrically about the bushings. This simple construction becomes, however, inadequate where the current in the high voltage lead is low, such as is the case in all the high voltage transformer and circuit breaker stations wherein the problem of the provision of suitable instrument transformers is most acute, inasmuch as the current in the single-turn primary is not sufficient to produce the flux required for satisfactory operation of transformers. In such cases, the construction of the instrument transformers becomes very cumbersome and expensive, and renders the high voltage apparatus more complicated than is desirable from the standpoint of satisfactory operation.

The objects of my invention aim at the provision of an improved instrument transformer of the foregoing character that will avoid the deficiencies of the prior-art constructions, and that will permit the construction of high voltage transformer windings of any desirable number of turns, with bushings of the ordinary type, such as have been used heretofore in instrument transformers operated with single-turn high voltage primaries. According to my invention, the laminated

iron core of the transformer, or a portion of the magnetic circuit thereof, is placed in the interior of the bushings so that the lead wire extending through the bushings may be wound around the core portion to form a coil having as many turns as are necessary. A suitable secondary winding is arranged on the core, preferably in the interior of the bushing, to co-operate with the high voltage winding, the bushings being filled with oil, and suitable barriers being provided between the windings and the cores so as to fully insulate the high-voltage winding against the low-voltage winding and the core. 65

My invention may be embodied in a variety of constructions some of which are shown, by way of example, in the accompanying drawings wherein

Fig. 1 is a vertical sectional view of a bushing transformer and a portion of the high voltage apparatus made according to the invention;

Fig. 2 is a transverse sectional view through the transformer of Fig. 1 along the line II-II;

Figs. 3 and 4 are views similar to Fig. 1 showing modifications of the invention;

Fig. 5 is a view similar to Fig. 2 through the transformer of Fig. 4 along the line V-V; 80

Figs. 6 and 7 are views similar to Fig. 1 of further modifications of my invention.

As pointed out above, the principal feature of the invention resides in the solution of the difficulties experienced in the provision of instrument transformers in conjunction with simple lead bushings. These difficulties are solved by mounting the whole, or the main portions of the instrument transformer in the interior of the hollow insulator bushing of the type normally used in high voltage apparatus.

In the exemplification of the invention shown in Fig. 1, a bushing for a high voltage apparatus having, as usual, a metallic casing 1 comprises a pair of vertically disposed coaxially mounted tubular insulating members 3 and 4, having their inner ends 5 and 6 arranged to telescopically slide one within the other. The inner end 5 of the upper insulating member 3 is arranged to fit over the end

6 of the lower insulating member 4, so as to protect the interior chamber formed by the two insulating members from moisture, or rain, or other undesirable influences.

5 The two tubular insulating members are united into a single bushing by means of a pair of metallic flange members 7 and 8, which are suitably cemented to the upper and lower insulating members, respectively, the flanges 7 and 8 being tightly joined to each other to prevent escape of insulating liquid, such as oil, which fills the hollow chamber 9 of the bushing. The laterally projecting flanges 7 and 8 are suitably clamped to the walls of the casing 1 of the high voltage apparatus.

As pointed out above, the essential feature of the invention resides in the mounting of the principal elements of the instrument 20 transformer within the interior of the bushing so as to permit the utilization of multi-turn primary windings, without recourse to special complicated construction. In the exemplification of the invention shown in Fig. 1, this is achieved by providing a suitable shell-type laminated magnetic core, as shown in detail in Fig. 2, having a central core leg 11, with a circular core portion 12 constituting the return magnetic paths for the flux 30 induced in the central core portions. Instead of the specific shape and construction of the transformer shown in Fig. 2, any other suitable transformer construction may be used. Immediately adjacent the central core leg 11 there is provided a low voltage transformer winding 13 having suitable leads which may be connected to the metering and switching equipment in any approved manner, while the high voltage winding of the transformer 40 is constituted by a number of turns 15 of the lead wire wound around the central core and insulated from the core portions and from the low-voltage winding by means of insulating tubes 16, of porcelain for instance, the insulating tubes extending through the semi-circular spaces between the central core 11 and the outer circular core portion 12. The free ends 21, 22 of the upper and lower tubular insulating members 3 and 4 are enclosed 50 by suitable metallic closure members 23, 24, to which the ends of the lead wire 15, constituting the high-voltage coil of the transformer in the interior of the bushing are connected, so that the interior-closure member 55 24 may be used as a terminal connection to the high-voltage apparatus in the interior of the casing, while the outer-closure member 23 may be used as the exterior terminal of said apparatus.

60 A distinct feature of the invention resides in the simple arrangement for holding or supporting the transformer core within the hollow chamber in the interior of the bushing, so as to prevent short circuits or other 65 defects that may result from accidental dis-

placement of the parts within the interior of the bushing. This improved mounting also permits ready dismantling of the bushing and the removal of the transformer from within the interior of the bushing for overhauling or repair, without necessitating the removal of the entire bushing from the casing.

To this end the transformer is so arranged as to be directly or indirectly held in place by intermediate conducting flange members 7 and 8 which join the upper porcelain tube 3 to the lower porcelain tube 4 of the bushing. In the exemplification of the invention shown in Fig. 1, the circular core 12 is clamped between the inwardly projecting shoulder or ledge 26 of the upper insulator, and the upper edge of the tubular end portion 6 of the lower insulator 4, which projects into the interior of the upper insulator. The pressure required to hold the annular magnetic core 12 between the two porcelain members is supplied by the means which serve to clamp the flanges 7 and 8 to each other, the metallic clamping members thus serving indirectly to hold the transformer in place. In order to disassemble the bushing for inspection or repair of the transformer, it is sufficient to release the bolts or other means with which the upper flange 7 is held to the lower flange 8. The upper bushing member 3 may then be removed and the transformer core 11-12 with the associated windings readily dismantled.

The bushings that are ordinarily used on high voltage have a filling of oil or other insulating liquid in order to effectively insulate the high-voltage lead wires 15. The present improved mounting of the instrument transformer within the bushing represents very marked advantages in cases where air or 105 gaseous insulation within the bushing is sufficient.

In Fig. 3 is shown a form of the invention in which the lower half of the bushing insulator is omitted, the casing 1 of the high-voltage apparatus being entirely filled with oil, which also extends towards the top of the bushing. The bushing comprises a tubular insulator 31 having a flange member 32 cemented to the lower open end thereof, for joining the bushing to the walls of the apparatus casing 1. A current transformer of similar construction as that shown in Figs. 1 and 2, has the magnetic core 12 held in place by clamping the same between the inner edge 115 of the casing 1 and the upper flange end 33. The top of the tubular insulating bushing 31 has a constricted end portion which is sealed by a glass cap 34 for determining the level of the oil in the bushing, enough oil always being maintained in the bushing and the casing so that the upper level thereof is visible in the glass cap 34.

The bushing shown in Fig. 4 comprises two similar shell halves 41, 42, which are 120

joined to each other by means of flanges 43, 44. The iron core 12 of the current transformer is held between the flanges by means of a ring 45 which extends from the core into the space between the opposing surfaces of the flanges.

The bushing shown in Fig. 4 is also distinguished by a modified construction of the tubular porcelain insulator for insulating the high-voltage turns of the lead-in wires from the low-voltage winding and the core of the instrument transformer.

As shown in Fig. 5, the insulating tubes have the form of semi-circular cylinder sections 46 similar in shape to the spaces between the central core member and the outer circular-core member of the instrument transformer. The two tubular insulator members 46 are joined by cross members 47 to form a single piece and are held in place between suitable projecting shoulders 48 of the upper and lower halves of the bushing. In view, however, of the integral construction of the two insulated tubes 46, the transformer core cannot be constructed from single-piece laminations.

In the arrangement shown in Figs. 4 and 5 the middle leg 48' of the transformer is made distinct from the circular core portion, the circular core portion having inwardly extending chamfered projections 49 against which abut similarly shaped end surfaces of the middle core leg. This construction insures a satisfactory magnetic joint between the core members, the joint being still further improved through the magnetic attraction of the core portions.

In the modification of the invention shown in Fig. 6 the upper and lower bushing halves 51, 52, are joined by means of flanges, 53, 54, having cylindrical extension members 55, 56, that are cemented to the interior wall surfaces of the bushing members, the magnetic core 12 of the transformer being secured to the inner portions of the flanges within the bushing.

In the modification of the invention shown in Fig. 7, the bushing is formed of an upper tubular insulating member 61 and a lower insulating member 62 which are mounted coaxially with each other by means of an intermediate tubular member 63 of iron or similar conducting material, the intermediate member being cemented to the adjacent ends of the upper and lower insulating members 61 and 62. The bushing is mounted on the casing of the high-voltage apparatus by means of a flange 65 laterally extending from the intermediate metallic portion of the bushing. The instrument transformer in the interior of the bushing is held in place by clamping the transformer core 12 to a shelf member 66 extending from the walls of the intermediate metallic tube 63 towards the center of the bushing. The upper insulator is not

constricted at its top end as in the other constructions described before, but is sufficiently wide to permit the removal of the instrument transformer with lead-in wires 15 from the interior of the bushing, after the cap 67, 70 which is clamped to the top of the bushing, has been removed.

I claim as my invention:

1. A lead-in bushing for high-voltage apparatus comprising a tubular insulating member, said insulating member being closed at its ends to constitute a closed chamber, a lead-in conductor extending through said tubular member between the ends thereof, a magnetic core member disposed in the interior of said chamber, said lead-in conductor being wound around said core member to constitute a transformer winding, an additional winding wound around said core member to operate in transformer relationship with the said first-mentioned winding, and insulating means disposed between the portions of the lead-in conductor adjacent to said core member within the interior of said bushing. 75

2. A lead-in bushing comprising a pair of coaxial insulating tubes, means for joining said tubes to each other, the free ends of said tubes being sealed, a lead-in conductor extending through said bushing between such ends thereof, a magnetic core member disposed in the interior of said bushing, said lead-in conductor constituting a transformer winding wound around said core member, and another winding wound around said core member to operate in transformer relationship with said first-mentioned winding, said core member being held in place by said means for joining said tubes. 90

3. A lead-in bushing for high-voltage apparatus comprising a pair of coaxial tubular insulators, an annular metallic member uniting said tubular insulators, said tubular insulators being closed at their ends to constitute in conjunction with said metallic member a closed chamber, a lead-in wire extending through said chamber between the ends of said tubular insulators, a transformer core disposed in said chamber and held in place by said metallic member, said lead-in conductor constituting a transformer winding 105 110 wound around said core, and an additional transformer winding wound around said core to co-operate with said first-mentioned winding. 115

4. In high-voltage apparatus, a casing, a lead-in bushing extending through a wall of said casing, said lead-in bushing comprising a pair of insulating tubes, a circular conducting member disposed coaxially with said tubes, means for securing said conducting 120 member to the walls of said casing, the free ends of said tubes being sealed to form a closed chamber, a lead-in conductor extending through said chamber between such ends thereof, a magnetic transformer core dis- 125 130

posed in the interior of said chamber and held in place by said conducting member, said lead-in conductor constituting a primary winding wound around said core, and an additional winding wound around said core in transformer relationship with said first-mentioned winding.

5. A combination as defined by claim 4 characterized by a filling of insulating liquid in said bushing chamber.

In testimony whereof I have hereunto subscribed my name at Mannheim, November 23, 1926.

FRITZ ANDORFF.
